ATTORNEY.

UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

FUSIBLE DEVICE.

1,147,031.

Specification of Letters Patent. Patented July 20, 1915.

Application filed May 21, 1910. Serial No. 562,748.

To all whom it may concern:

Be it known that I, ALBERT J. LOEPSINGER, of Providence, in the county of Providence and State of Rhode Island, have invented 5 certain new and useful Improvements in Fusible Devices; and I do hereby declare the following specification, taken in connection with the accompanying drawings, forming a part of the same, to be a full, clear, and exact 10 description thereof.

The present invention relates to a fusible device such as is employed for holding closed the valve of an automatic sprinkler or fire extinguisher, or in connection with other 15 automatic fire extinguishing apparatus.

The invention relates more particularly to that form of fusible device which is composed of three members, usually termed a post, a lever, and a key, for reducing the 20 strain upon the fusible solder joint, as for example the form of fusible device employed for holding the valve closed in the well-known Grinnell sprinkler.

In a device of this character, and in which the key-member has a tendency to rock under the strain to which the strut is subjected, the greatest strain upon the solder joint comes at the lower end of said key-member, and particularly at the lower edge of what 30 may be termed the anchor portion of said key-member.

The object of the present invention is to strengthen the fusible solder joint in a device of this character, and particularly the 35 joint between the anchor portion of the key-member and the post member of said device.

To that end the invention consists primarily in providing the anchor portion of the key member of such device with a lateral 40 projection at its end to thereby facilitate the building up at this point of a ridge or mound of fusible solder, and thereby strengthen the joint between such anchor member and the post member of the device.

The invention further consists in providing the anchor portion of the key-member at its end with slots, thereby forming tongues or teeth which serve to increase the extent 45 of the edge of such anchor portion to which the solder can be applied and also to provide recesses within the compass of such anchor portion, within which recesses an additional amount of solder may be received.

The invention further consists in providing 50 the anchor portion of the key member

at its end with slots and in providing the intermediate tongues or teeth formed thereby with lateral projections.

The invention further consists in providing the anchor portion of the key-member 60 at its end with slots and in providing the post-member of the device with corresponding or registering slots or perforations to thereby render possible the formation of what may be termed a rivet of solder to 65 unite the anchor portion of said key member to said post member.

The invention further consists in certain 70 constructions and combination of parts hereinafter described and claimed.

Referring to the drawings, Figure 1 represents a Grinnell automatic sprinkler provided with a fusible device embodying the present invention; Fig. 2 is a front view, and Fig. 3 an edge view upon an enlarged 75 scale of a portion of the post member and of the anchor portion of the key member of a fusible device embodying certain features of the present invention, the fusible solder being shown as applied in Fig. 3; and Figs. 4 80 and 5 are corresponding front and edge views of a portion of the post member and of the anchor portion of the key member embodying a further features of the invention, the fusible solder being shown as applied in Fig. 5. 85

In the sprinkler shown in Fig. 1 the body portion 1 with the screw-threaded neck 2, the yoke 3, and deflector 4 are or may be all of the usual construction. So also the fusible device is of the usual construction in the respect that it comprises three members, viz., the post 5, lever 6, and key 7, said key-member being provided with an anchor portion 8 adapted to be secured by fusible 90 solder to the face of the post member 5.

Referring first to the construction shown in Figs. 2 and 3, the anchor portion 8 of the key-member is provided with slots 9 forming the tongues or teeth 10. The lower ends 100 of these tongues are bent outward or otherwise provided with outward or lateral projections 11. The fusible solder is applied in the form of a ridge or mound 12, as shown in Fig. 3.

The construction shown in Figs. 4 and 5 is the same as that shown in Figs. 2 and 3, and the corresponding parts are therefore similarly numbered, with the exception that the post member 5^a is also provided with 110

slots or perforations 9^a corresponding to and registering with the slots 9 in the anchor portion of the key-member 7. The slots in said post-member are, however, preferably 5 made somewhat longer than the slots 9 in the key-member, and so as to extend somewhat below the end of said key-member, as shown in Figs. 4 and 5. With this construction the fusible solder extends through 10 the slots 9^a in the post-member and is formed into a ridge or mound 12^a on the opposite side of said post-member.

With the construction above described, and as shown both in Figs. 2 and 3 and also 15 in Figs. 4 and 5, the slots in the anchor portion of the key-member form an extended edge at the end of said key-member and also form recesses, when the parts are assembled, adapted to receive an additional 20 amount of the fusible solder, while the outward or lateral projections 11 constitute a core or cores, so to speak, about which the ridge or mound of solder 12 may be built up, thereby providing a much stronger solder 25 joint at this point than has heretofore been possible. It is evident that, if desired, the slots 9 may be omitted, in which case there would be a single continuous outward or lateral projection about which the ridge or 30 mound of solder may be built up in the same manner. So also, if desired, the lateral projection or projections may be omitted and only the slots in the anchor portion of the key-member be employed. It is preferred, 35 however, to employ both the outward projection or projections and also the slots, and it has been found that by so doing the solder-joint is still further strengthened.

When the post-member of the device is 40 also provided with registering slots or perforations, as shown in Figs. 4 and 5, the fusible solder passes through said slots and may also be built to form a ridge or mound of solder on the opposite side of said post-member, the formation of such ridge or 45 mound on this side being facilitated by providing the pincers with which the parts are held during the soldering operation with a mold or depression to receive the solder. 50 With this construction the fusible solder takes substantially the form of a headed rivet, which serves to still further strengthen the solder joint and the fusible union between the anchor portion of the key-member 55 and the post-member of the device. It will be understood that if such a rivet formation of the solder is to be produced it will be de-

sirable to hold the parts in a horizontal position during the soldering operation, with the anchor portion of the key-member up- 60 permost.

It will be understood that the shape, size, 65 number and location of the slots in the key-member and in the post-member, respectively, may be varied as desired.

What I claim as my invention and desire to secure by Letters Patent is:

1. A fusible device comprising a post-member, a lever-member, and a key-member extending through said post-member and 70 having an anchor portion lying parallel with said post, said anchor portion being provided with a lateral projection about which the fusible solder may be built.

2. A fusible device comprising a post-member, a lever-member, and a key-member extending through said post-member and 75 having an anchor portion lying parallel with said post, said anchor-portion being provided with slots to receive the fusible solder. 80

3. A fusible device comprising a post-member, a lever-member, and a key-member extending through said post-member and having an anchor-portion, said anchor-portion being provided with slots and also with 85 a lateral projection about which the fusible solder may be built.

4. A fusible device comprising a post-member, a lever-member, and a key-member extending through said post-member and 90 having an anchor-portion, said anchor-portion being provided with slots and having the tongues formed thereby provided with lateral projections.

5. A fusible device comprising a post-member, a lever-member, and a key-member extending through said post-member and having an anchor-portion, said anchor-portion being provided with parallel open-ended slots and said post-member being provided with slots registering with the slots in said key-member. 95

6. A fusible device comprising a post-member, a lever-member, and a key-member having an anchor-portion, said key-member 100 being provided with slots and also with lateral projections, and said post-member being provided with slots registering with the slots in said key-member. 105

ALBERT J. LOEPSINGER.
